STAND FOR TIERSABLE STOCK BOXES

Paul F. Nydegger, Westfield, and John L. Huey, Elizabeth, N. J., assignors to The Singer Manufacturing Company, Elizabeth, N. J., a corporation of New Jersey

Application March 9, 1945, Serial No. 581,922

4 Claims. (Cl. 248—146)

1

This invention relates to stock boxes and it has as its primary object to provide a strong, lightweight and durable stock box which may be manufactured at a relatively low cost.

Another object of the invention is to provide improved skid-supported stock boxes capable of being stacked in tiers and which, when so stacked, will be locked together against relative sidewise and endwise movement.

Another object is to provide a combined tiersable stock box and supporting base or skid, which is so constructed and arranged that the base of one unit is adapted to be readily fitted over and supported upon the top of the box portion of a similar unit.

A further object of the invention is to provide a combined tiersable stock box and supporting skid, which, when a plurality of them are stacked in a tier, will afford a relatively large space between the lowermost box and the floor for the insertion of the lifting element of a platform truck, and a relatively smaller space between the adjacent boxes for the insertion of the lifting element of a fork truck.

A still further object is to provide a combined tiersable stock box and supporting skid in which the skid portion is made primarily of sections of relatively lightweight angle iron suitably shaped and secured together, for example, as by welding, and in which certain parts thereof are reinforced and stiffened by brace-plates welded to said angle irons.

With the above and other objects in view, as will hereinafter appear, the invention comprises the devices, combinations and arrangements of parts hereinafter set forth and illustrated in the accompanying drawings of two embodiments of the invention, from which the several features of the invention and the advantages attained thereby will be readily understood by those skilled in the art.

In the drawings, Fig. 1 is a side elevation of one form of skid-supported stock box embodying the present invention and showing, in dotted lines, the skid portion of a similar unit tiered thereon.

Fig. 2 is a perspective view of the skid portion of the stock box shown in Fig. 1.

Fig. 3 is an enlarged detail sectional view taken on the line 3—3 of Fig. 1.

Fig. 4 is an enlarged detail sectional view taken on the line 4—4 of Fig. 1.

Fig. 5 is an enlarged perspective view of one end of one of the cross-rails and a portion of one leg of the skid shown in Fig. 2.

2

Fig. 6 is a detail sectional view taken on the line 6—6 of Fig. 4.

Fig. 7 is an enlarged detail sectional view taken on the line 7—7 of Fig. 1.

Fig. 8 is a side elevational view showing two skid-supported stock boxes, of slightly different construction from that shown in Fig. 1, tiered one upon the other.

Fig. 9 is an end view of the tiered stock boxes shown in Fig. 8.

Fig. 10 is an enlarged detail sectional view taken on the line 10—10 on Fig. 8.

Fig. 11 is an enlarged detail sectional view taken on the line 11—11 of Fig. 9.

Fig. 12 is a vertical sectional view taken on the line 12—12 of Fig. 8.

Referring more specifically to the drawings and first to the embodiment of the invention illustrated in Figs. 1 to 7 inclusive, the improved stock

box unit is shown as comprising a receptacle B, or box proper, open at the top, and a supporting base or skid S, upon which the receptacle is permanently secured, as by welding, as indicated at w. The box B may be made as a single compartment or, if desired, it may comprise two compartments a and b, separated by a central partition p, preferably of wood, secured to angle irons i welded to the side walls of the box as illustrated in Figs. 1, 3, 4 and 6.

The side walls s and the end walls e of the box B are preferably made of sheet metal, the end walls being folded over and welded to the outer sides of the side walls, as indicated at f, Fig. 1.

The bottom of the box is closed by floor boards c supported by angle irons, later to be referred to, forming a part of the skid S. Wooden cleats k, secured to the inner face of the side walls s, overlie the floor boards c and prevent upward movement of the boards. At the top of the box, the

side walls s are folded over as at s' (Figs. 3 and 7) and are welded to angle irons j which strengthen and stiffen the box.

For certain purposes, as for example where it is desired to have access to the contents of the boxes while they are in tiered position, it may be desirable to omit a part or all of one or both of the side walls of the boxes or to provide sliding doors therein, as is common practice.

The skid or base S, to which the box B is permanently secured, is made of fabricated metal, principally angle irons, and comprises front and rear frame members 1 and 2 each consisting of a horizontally disposed box-supporting side rail 3 having downturned end portions 4, affording legs 55 for the base. The frame members are connected

together in the middle by a single inverted T-iron cross-brace 5 and, at each end, by three transversely and horizontally disposed angle iron cross-braces 6, 7 and 8. The cross-braces 6 are welded to the rails 3 and serve as supports for the ends of the box B and, together with the brace 5, to support the floor boards c. The cross-braces 8 are welded to the lower ends of the leg portions 4 and form feet therefor by which the individual box units may be supported upon a floor or other substantially level surface. The brace 7 is inverted, as compared with the braces 6 and 8, and is welded to the leg portions 4 at approximately one-third the distance between the side rails 3 and the lower ends of the legs. The members 7 serve not only as braces but also as means for supporting the base of one unit on the top edge of the box portion of another unit when the units are stacked or tiered, as indicated in dotted lines in Fig. 1.

Each end of each of the braces 7 is notched, as indicated at 9 in Fig. 5, and the vertical wall 7^a thereof is bent outwardly in the form of a lug 10 which is welded to the outside of one of the legs 4. The upper wall 7^b of each of the braces 7 extends outwardly beyond the plane of the lug 10 and is turned downwardly to form a stop 11 which, when the units are tiered, as indicated in dotted lines in Fig. 7, lies adjacent the side wall s of a lower unit and prevents any material lateral displacement of the units. The walls 7^a of the members 7 likewise lie adjacent the outer face of the end walls e of a lower box and prevent any material endwise movement of one unit relative to the other.

As above indicated, the leg portions 4 are formed integral with the side rails 3. To enable the leg portions to be bent approximately ninety degrees to the side rails, a cut is made through the vertical wall of the rails and thereafter the horizontal wall is bent, in line with the cut as shown at x in Fig. 2, thus forming substantially a right angle between the surfaces y and z.

The lower portion of the legs 4 are bent outwardly from the plane of the upper portion thereof as indicated most clearly at n in Figs. 1 and 11, thus facilitating the placing of the base of one unit on the top of the box portion of another unit in the tiering of such units.

It is to be understood that the cutting and bending of the angle irons to form the downturned leg portions 4 is done prior to the beginning of the assembling of the component parts of the skid.

To strengthen and stiffen the frame members 1 and 2, brace plates 12 are welded to the outside of those members in the region where the legs 4 join the side rails 3.

The form of the invention illustrated in Fig. 8 to 12 inclusive, differs from that above described principally in the construction of the box B per se. In this form the body of the box, comprising side walls t and end walls u, is made mainly of wood and preferably of hardwood plywood instead of sheet metal as in Figs. 1 to 7.

Aside from a combined side brace and box hold-down element, later to be described, the skid portion of the unit shown in Figs. 8-12 is the same as that shown in Figs. 1-7. To the extent that the two embodiments of the invention are alike the same reference characters have been applied thereto.

As shown in Figs. 8-12 the vertical corners of the box B are reinforced with sheet metal angle

irons 13 secured to the box by rivets 14. The upper edge of the box is bound by an inverted U-shaped channel iron 15 upon which the angle irons 1 of another unit are adapted to rest when the units are tiered.

To strengthen the unit and prevent separation of the box from the skid, the unit is provided with two upstanding side brace and box hold-down elements 16, having their inturned bottom ends 16^a welded to the under side of the side rails 3. The elements 16 are secured to the side walls of the box, as by rivets 17, and have their upper ends bent over the top edge of the box and riveted thereto, as shown at 18 in Figs. 8 and 12.

It has been found that, in actual practice, stock boxes constructed in accordance with this invention are strong, durable, of relatively lightweight, and may be manufactured at a fraction of the cost of comparable stock boxes now on the market.

When built in accordance with this invention, a stock box 36 inches long, 21½ inches wide and 24½ inches high, having a content of over ten cubic feet, has an approximate weight of only 65 pounds and will sustain a load of 6000 pounds. Thus the boxes may be loaded with 1500 pounds each and safety stacked in tiers of four.

Likewise stock boxes as disclosed herein are adapted to be tiered with a minimum loss of space due to the fact that the base of one unit fits down over and in effect, telescopes with the top of the box of an underlying unit so that there is only about 3½ inches between the top of the box of one unit and the bottom of the box of an overlying unit.

An important feature of this invention is the construction of the skid portion of the unit. As shown particularly in Figs. 1, 2 and 8 the base, or skid, S is of inverted flattened U-shape in side elevation. This affords an open space or clearance, designated as C (Figs. 1 and 8), approximately 28 inches long and 12 inches high, between the legs 4 and between the side rails 3 of the lowermost skid and the floor, into which space may be inserted the lifting element of a platform truck when it is desired to move an entire tier of boxes. The skid is also so constructed that a space, designated F, approximately 18 inches long and 3½ inches high is afforded intermediate the legs 4 and between the angle iron cross-braces 6 and 7. This space affords clearance for insertion of the lifting element of a fork truck in the tiering of the units or when it is desired to remove one or more of the units from the tier.

Having thus set forth the nature of the invention, what we claim herein is:

1. A base member for a stock box unit, comprising a fabricated metal framework including front and rear frame members of substantially inverted U-shape in side view, each of said frame members including a box-supporting rail having, at each end, a downturned and outwardly flared leg portion; upper cross braces connecting said frame members at the upper ends of said leg portions, said upper cross braces serving as box-supporting members; lower cross braces connecting said frame members at the extreme lower ends of said leg portions and serving as feet therefor; and reinforcing brace plates secured to said box supporting rails and leg portions.

2. A base member for a stock box unit having a receptacle, comprising a fabricated metal framework including front and rear frame mem-

bers of substantially inverted U-shape in side view, each of said frame members including a box-supporting rail having, at each end, a down-turned leg portion; upper and lower cross braces connecting said frame members at the upper and lower ends of said leg portions, the upper ones of said cross braces also serving as box-supporting members; and a third cross brace connecting said side frames intermediate said upper and lower cross braces, said third cross brace also serving to support the base on the top of the receptacle of a similar unit.

3. A base member for a stock box unit having a receptacle, comprising a fabricated metal framework including front and rear frame members of substantially inverted U-shape in side view, each of said frame members including a box-supporting rail having, at each end, a down-turned leg portion; upper and lower cross braces connecting said frame members at the upper and lower ends of said leg portions, the upper ones of said cross braces also serving as box-supporting members; and a third cross brace, of inverted L-shape in cross section and having downturned end portions, connecting said side frames intermediate said upper and lower cross braces, said third cross brace also serving to support the base on the top of the receptacle of a similar unit, the vertical walls and the downturned end portions of said third cross braces being adapted to engage the end and side walls, respectively, of the underlying receptacle to prevent material endwise or sidewise movements of said units relative to each other.

4. A base member for a stock box unit, comprising a fabricated metal framework including front and rear frame members of substantially inverted U-shape in side view, each of said frame members including a box-supporting rail having, at each end, a downturned leg portion; upper cross braces connecting said frame members at the upper ends of said leg portions; said upper cross braces serving as box-supporting members, and lower cross braces connecting said frame members at the extreme lower ends of said leg portions and serving as feet therefor.
